UNITED STATES PATENT OFFICE.

ALEXANDER ROSS, OF ROCHESTER, NEW YORK.

AUDIPHONE.

SPECIFICATION forming part of Letters Patent No. 613,606, dated November 1, 1898.

Application filed December 18, 1897. Serial No. 662,427. (No model.)

To all whom it may concern:

Be it known that I, ALEXANDER ROSS, a resident of Rochester, in the county of Monroe and State of New York, have invented 5 certain new and useful Improvements in Audiphones; and I do hereby declare the following to be a full, clear, and exact description of the invention, such as will enable others skilled in the art to which it pertains to make 10 and use the same.

The invention relates to audiphones, and has for its object to increase their acoustic sensitiveness and efficiency.

The invention consists in the construction 15 hereinafter described and pointed out.

In the accompanying drawings, Figure 1 is a central longitudinal section. Fig. 2 is a plan of a ring and its contained diaphragm. Fig. 3 is a plan of another diaphragm on an 20 enlarged scale, diaphragm-supporting wires being shown in section. Figs. 4 and 5 are plans of reticulated diaphragms. Fig. 6 is an enlarged central longitudinal section of the main diaphragms and their supporting 25 device. Fig. 7 shows a modification.

Numeral 1 denotes the trumpet - shaped body, preferably curved, as shown.

2 indicates the receiving end, and 3 the ear-entering end of the said body.

30 4 and 5 denote reticulated screens, preferably made of very fine silver wire. These guard the interior of the instrument and prevent the entrance of insects or other objects that might obstruct or injure the interior 35 mechanism or that might enter the ear when the audiphone is in use. The screens are situated at each side of the interior mechanism to prevent insects from hiding or nesting therein. Single screens have been heretofore used to 40 prevent entrance of insects to the ear from the exterior of the trumpet-shaped body; but such device entirely fails of the important function secured by a plurality of screens placed as shown, whereby the secret lodgment of insects in the body and in a situation to enter 45 the ear when the instrument is in use is obviated. The distance of the diaphragm 4 from the adjacent exterior opening is so small that the adjacent interior can be inspected 50 and insects dislodged, if necessary, which, however, is not true of the more remote interior.

6 denotes a compound ring made of separate rings of different metals—as, for example, zinc 6' and copper 6".

55

7 is a diaphragm made, preferably, of finely-tempered steel and very thin or about the thickness of tissue-paper. Its edges are scalloped, as at 8, and it is supported within the ring 6 by the fingers or points 9, which separate the scallops.

10 indicate wires which connect the diaphragm 7 with a smaller diaphragm 11, also made very thin and of tempered steel. These wires, which are preferably magnetic, are 65 nicked at 12 to receive the edge of the diaphragm 11 and support the same. Beyond said latter diaphragm, toward the ear-entering end of the instrument, the wires 10 are bent outwardly into contact with the wall of 70 the trumpet, as shown. These wires, which preferably are magnets, are connected meditately to the ring, which resembles a voltaic pile and acts to maintain the magnetism of the ring, by which means the sensitiveness of 75 the device is increased. Further, the material of which the diaphragm is composed, made thin, as stated, is particularly adapted to transmit sound-waves. The diaphragms being supported at their edges, one by and 80 between the wires and the other by means of circumferential fingers 9, are rendered specially sensitive to air or sound waves by said manner of support.

The openings in diaphragm 7 around its periphery permit air or sound waves to freely enter. These are concentrated by the inclosing wall upon the small diaphragm, which thereby and by reaction from diaphragm 7 is vibrated in unison with said latter diaphragm, 90 which first receives the impulses entering the mouth of the instrument. The vibrations are transmitted from diaphragm 11 to the interior of the ear. This diaphragm is preferably placed within half an inch of the ear-entering end and will in use be situated within 95 the circumference of the outer ear.

The screens are made of non-corrodible resonant metal and of fine mesh to exclude foreign objects. Such screens do not seriously interfere with the acoustic properties of the instrument.

Preferred materials have been mentioned herein, but others are not excluded, neither

100

are mere mechanical changes which do not substantially alter the construction and operation.

Having described my invention, what I claim is—

1. In an audiphone, the combination of a trumpet-shaped body, devices for multiplying sound, and a plurality of screens located wholly within the trumpet-shaped body intermediate its ends, one of the screens being situated on one side the sound-multiplying devices near the small or ear end of the body and the other screen situated adjacent said devices on the opposite side thereof and remote from the trumpet-mouth, substantially as described.
2. In an audiphone, the combination of a trumpet-shaped body, a plurality of vibratory diaphragms of less diameter than the adjacent parts of the trumpet-body and having separate points in their peripheries connected to the trumpet-body the intermediate parts of the periphery being disconnected therefrom, substantially as described.
3. In an audiphone, the combination of a trumpet-shaped body, a plurality of vibratory diaphragms of less diameter than the adjacent parts of the trumpet-body and having separate points in their peripheries connected to the trumpet-body, the intermediate parts of the periphery being disconnected therefrom, and wires connecting the diaphragms, substantially as described.
4. In an audiphone, the combination of a

trumpet-shaped body, a ring composed of alternate rings of different metals, a vibratory diaphragm connected to said ring, a second diaphragm and metallic wires connecting the diaphragms, substantially as described.

5. In an audiphone, the combination of a trumpet, a ring composed of alternate rings of different metal, a vibratory diaphragm connected to said ring, a second diaphragm, and means for connecting the diaphragms, said means consisting of wires attached at or near their peripheries and touching the body at their ends, substantially as described.

6. In an audiphone, the combination of a trumpet, a diaphragm and wires supported within the trumpet, said diaphragm being supported by said wires engaging its periphery, substantially as described.

7. In an audiphone, the combination of a trumpet, a ring composed of different metals arranged alternately, a scalloped diaphragm having fingers between its scallops supported by the ring, wires extending from the fingers to a remote part of the trumpet-wall, and a diaphragm of less diameter than the adjacent part of the trumpet having its edge supported by the wires, substantially as described.

In testimony whereof I have signed this specification in the presence of two subscribing witnesses.

ALEXANDER ROSS.
